(57) **CLAIM**

The ornamental design for a compact transmitter apparatus, as shown and described.

DESCRIPTION

FIG. 1 is a front perspective view of a compact transmitter apparatus according to the present invention;

FIG. 2 is a rear perspective view thereof;

FIG. 3 is a front elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a rear view thereof.

The broken lines are for illustrative purpose only and form no part of the claimed design.
